(57) **CLAIM**

The ornamental design for a soil tamping implement, as shown and described.

DESCRIPTION

FIG. 1 is a perspective view of our soil tamping implement;

FIG. 2 is a bottom plan view thereof;

FIG. 3 is a front side elevation view thereof;

FIG. 4 is a top plan view thereof; and,

FIG. 5 is a right side elevation view thereof.

The broken line showing is for illustrative purposes only and forms no part of the claimed design.
